UNITED STATES PATENT OFFICE.

CHESTER H. THORDARSON, OF CHICAGO, ILLINOIS.

SPARK-COIL.

958,899.

Specification of Letters Patent. Patented May 24, 1910.

Application filed September 3, 1907. Serial No. 391,023.

REISSUED

To all whom it may concern:

Be it known that I, CHESTER H. THORDARSON, a citizen of the United States, residing at Chicago, in the county of Cook, State of Illinois, have made a certain new and useful 5 Invention in Spark-Coils, of which the following is a specification.

This invention relates to spark coils.

The object of the invention is to provide 10 an ignition, impedance, spark or kick coil of simple construction and efficient in operation.

A further object of the invention is to provide a coil of the character referred to 15 having a divided magnetic circuit and a winding of least resistance and fewest turns, therefore, of least self induction, capable of storing up considerable energy and dissipating the same in the spark whereby comparatively little power is lost.

Other objects of the invention will appear more fully hereinafter.

The invention consists substantially in the construction, combination, location and relative arrangement of parts all as will more 25 fully appear hereinafter, as shown in the accompanying drawing and finally pointed out in the appended claims.

Referring to the accompanying drawing 30 and to the various views and reference signs appearing thereon, Figure 1, is a view in side elevation of an ignition or spark coil embodying the principles of my invention. Fig. 2, is a view partly in top plan and partly in section on the line 2/2, Fig. 1 looking in the direction of the arrows. Fig. 3 is a view in transverse section on the line 3, 3, Fig. 2 looking in the direction of the arrows. Fig. 4, is a view in transverse 40 section showing a modified construction of core embraced within the spirit and scope of my invention.

The same part is designated by the same reference sign wherever it occurs throughout the several views.

When a closed iron ring of uniform transverse sectional area and material is magnetized in such a way that the magnetic flux is parallel with the ring, such a ring, does 50 not demagnetize when the current is broken even when made of soft iron. Such a ring can be partially demagnetized with hammer blows and completely demagnetized by current flowing in reverse direction around it. 55 Such a ring therefore is not the most eco-

nomical or efficient or desirable for use in connection with ignition, spark or impedance coils for the reason that the stored up energy in the magnetic circuit thereof is not dissipated in the spark, and hence considerable magnetic power is lost, being retained in the iron of the ring. If, however, an air space or gap is provided transversely through the body of the ring, such ring will demagnetize when the magnetizing circuit 60 is broken, the speed of demagnetization depending on the quality of the iron in the ring or the sub-division of the body thereof into wires or laminations. Ignition, spark or impedance coils employing a magnetic 65 circuit so sub-divided into wires or laminations and having air gaps or spaces formed transversely therethrough at convenient points, attain the highest degree of efficiency, that is, the spark produced from such 70 coil is longer and hotter with less consumption of battery power for the reason that when the electric circuit through the coil is broken the flux of the magnetic circuit which is stored up in such circuit, releases 75 or closes on the coil and hence augments the spark produced. In other words, energy is stored up in the magnetic circuit which energy is transformed into the spark.

It is among the special purposes of my 80 present invention to provide an ignition, spark or impedance coil embodying these characteristics and features.

The principles above referred to and outlined may be embodied in many specifically 85 different constructions. While, therefore, I have shown specific forms of apparatus embodying the principles of my invention, I desire it to be understood that said principles might well be embodied in other 90 specific forms of construction and still fall within the spirit and scope of my invention.

In the particular form shown, A, is a coil which may be of the usual or any well known 100 construction and arrangement for use in apparatus of this character. B, is the core around which said coil is wound. In practice, though in this respect my invention is not to be limited or restricted, I prefer to employ a sub-divided core. In Fig. 3, I 105 have shown the core made up of plates or laminations. In Fig. 4, however, I have shown the core, B', made up of wire rods or sections. The particular character of subdivisions of the core is therefore immaterial 110

in the broadest scope of my invention. The laminated form is preferable on account of cheapness of manufacture.

The magnetic circuit of the coil is completed through the side pieces, C. These side pieces extend on diametrically opposite sides and in parallel relation with respect to the axis of the coil and each side piece is provided at its ends with an inwardly turned portion, D, the inner faces thereof being arranged to bear against the core B, or B' at opposite ends of the coil.

In practice, and in order to effect in the most advantageous way the objects and purposes of my invention, I prefer to interpose insulating material in the air gap or space between the contacting end surfaces or faces of the portions D, and the juxtaposed surfaces of the core B, B', as indicated at E.

In practice and preferably the portions C, are sub-divided, though in this respect my invention is not to be limited or restricted and in the form shown the subdivisions are in the form of laminations or plates.

The side parts, C, may be held in assembled relation with respect to the core of the coil in any suitable or convenient manner. I have shown a simple and efficient way for accomplishing this result. Spring channel plates F, are slipped over each end of the coil core and the adjacent ends of the side parts C, as clearly shown in the drawing.

The provision of the air gaps or spaces between the contacting surfaces of the side parts C, and the core B, B', afforded by the interposing therebetween of the insulating strips E, enables the magnetic flux of the magnetic circuit to release or close on the coil when the electric circuit is broken, whereby the magnetic energy stored up in the metal of the magnetic circuit or the side pieces C, when the electric circuit of the coil is broken is transformed into heat to augment the spark produced by the break and which stored up energy is dissipated in the spark thereby making the spark longer and hotter and hence increasing the efficiency of the coil without increasing the consumption of battery power. In other words, by the construction described I am enabled to avoid the loss due to a failure in utilizing the magnetic flux of the magnetic circuit at the instant the spark is formed.

An ignition, impedance or spark coil embodying the principles of construction above set forth is designed and intended for use in any situation where such coils are desired. I do not desire, therefore, to be limited or restricted in respect to the uses to which my invention is to be put and in employing the term "spark coil" to designate my invention I intend to include the use of the device for any purpose for which it is adapted. It will also be seen that I am enabled to attain

the maximum efficiency with a coil of least resistance and fewest turns.

Having now set forth the object and nature of my invention and constructions embodying the principles thereof, what I claim as new and useful and of my own invention, I desire to secure by Letters Patent,

1. A spark coil having a laminated core, in combination with independent side pieces arranged to bear against the core at the ends thereof, and channel clips engaging the ends of the core and side pieces to retain the same in assembled relation.

2. A spark coil having a core and a subdivided side part formed with pole faces presented toward but separated from the ends of the said core and channel plates engaging the ends of said core and side part to hold the same in assembled relation.

3. A spark coil having a core, in combination with independent side pieces having pole faces arranged to bear against the sides of the core at the ends thereof, and means engaging the ends of the core and side pieces to retain the same in assembled relation.

4. A spark coil having a laminated core, in combination with independent side pieces having pole faces arranged to bear against the sides of the core at the ends thereof, and means for engaging the ends of the core and side pieces to retain the same in assembled relation.

5. A spark coil having a core, in combination with independent laminated side pieces having pole faces arranged to bear against the sides of the core at the ends thereof, and means engaging the ends of the core and side pieces to retain the same in assembled relation.

6. A spark coil having a laminated core, in combination with independent laminated side pieces having pole faces arranged to bear against the sides of the core at the ends thereof, and means engaging the ends of the core and side pieces to retain the same in assembled relation.

7. A spark coil having a core, in combination with independent side pieces having pole faces arranged to bear against the sides of the core at the ends thereof, insulating material interposed between the bearing surfaces of the core and side pieces, and means engaging the ends of the core and side pieces to retain the same in assembled relation.

8. A spark coil having a laminated core, in combination with independent side pieces having pole faces arranged to bear against the sides of the core at the ends thereof, insulating material interposed between the contacting surfaces of the core and side pieces, and means engaging the ends of the core and side pieces to retain the same in assembled relation.

9. A spark coil having a core in combination with independent laminated side pieces

having pole faces arranged to bear against the sides of the core at the ends thereof, insulating material interposed between the contacting surfaces of the core and side pieces, and means engaging the ends of the core and side pieces to retain the same in assembled relation.

10. A spark coil having a laminated core in combination with independent laminated side pieces having pole faces arranged to bear against the sides of the core at the ends thereof, insulating material interposed between the contacting surfaces of the core and side pieces, and means engaging the ends of the core and side pieces to retain the same in assembled relation.

11. A spark coil having a core, in combination with an independent side piece arranged in parallel relation with respect to the core and having pole faces at its ends directed toward and bearing against the side of the core at the ends of the latter, and means engaging the ends of the core and side pieces for retaining the same in assembled relation.

12. A spark coil having a core, in combination with independent side pieces arranged on opposite sides of the core and in parallel relation with respect thereto, the ends of the side pieces forming pole faces and being directed toward and bearing against the sides of the core at the ends of the latter, and means engaging the ends of

the core and side pieces for retaining the same in assembled relation.

13. A spark coil having a core, in combination with an independent side piece arranged in parallel relation with respect to the core, and having its ends forming pole faces and directed toward and bearing against the side of the core at the ends of the latter, an insulating strip interposed between the bearing surfaces of the core and side pieces, and means engaging the ends of the core and side pieces to retain the same in assembled relation.

14. A spark coil having a laminated core, in combination with independent laminated side pieces, arranged on opposite sides of the core and in parallel relation thereto, said side pieces having their ends forming pole faces and directed toward and bearing against the sides of the core adjacent the ends of the latter, insulating strips interposed between the bearing surfaces of the core and side pieces, and means engaging the ends of the core and side pieces to retain the same in assembled relation.

In testimony whereof I have hereunto set my hand in the presence of the subscribing witnesses, on this 27th day of July A. D., 1907.

CHESTER H. THORDARSON.
